What Hi Fi—Bose SoundTouch 300, announced Nov. 28, 2016 [online], [site visited Mar. 29, 2018]. Available from internet, URL: <<https://www.whathifi.com/bose/soundtouch-300/review>>.*
(Continued)*Primary Examiner* — Ian Simmons*Assistant Examiner* — Karra S Johnson(57) **CLAIM**

The ornamental design for soundbar, substantially as shown and described.

DESCRIPTION

FIG. 1 is a perspective view of a soundbar as seen from the front, top and side;

FIG. 2 is a front view thereof;

FIG. 3 is a rear view thereof;

FIG. 4 is a top view thereof;

FIG. 5 is a bottom view thereof;

FIG. 6 is an opposite side view thereof; and,

FIG. 7 is a side view thereof.

The dotted line portions of the drawings represent environmental structure only and form no part of the claimed design.
